DESIGN FOR A CUFF LINK

William J. Morse, Attleboro, Mass., assignor to
Morse Andrews Company, a corporation of
Massachusetts

Application August 3, 1937, Serial No. 70,806

Term of patent 14 years

To all whom it may concern:

Be it known that I, William J. Morse, a citizen of the United States, residing at Attleboro, in the county of Bristol and State of Massachusetts, have invented a new, original, and ornamental Design for Cuff Links, of which the following is a specification, reference being had to the accompanying drawing, forming part thereof.

In the drawing:

Fig. 1 is a side elevation of a cuff link showing my new design;

Fig. 2 is an end elevation;

Fig. 3 is a view similar to Fig. 1, the movable end being in upright position;

Fig. 4 is a side elevation of Fig. 3; and
Fig. 5 is a front elevation.

The characteristic feature of my design resides in the association of the torpedo-shaped head portion with side arms of the configuration shown.

I claim:

The ornamental design for a cuff link substantially as shown and described.

WILLIAM J. MORSE.
